C. H. COLSON

PARCEL POST COMPUTING SCALE

Filed April 12, 1920

INVENTOR
C. H. COLSON

BY *Carl W. Sinclair*

ATTORNEY

UNITED STATES PATENT OFFICE.

CHARLES H. COLSON, OF DES MOINES, IOWA.

PARCEL-POST COMPUTING SCALE.

Application filed April 12, 1920. Serial No. 373,129.

To all whom it may concern:

Be it known that I, CHARLES H. COLSON, a citizen of the United States of America, and resident of Des Moines, Polk County, Iowa, ⁵ have invented a new and useful Parcel-Post Computing Scale, of which the following is a specification.

The object of this invention is to provide an improved construction for a computing scale especially adapted for use in determining the weight and amount of postage required on parcel post packages. ¹⁰

A further object of this invention is to provide an improved separable housing for ¹⁵ a parcel post scale.

A further object of this invention is to provide improved means for conveniently suspending a scale.

A further object of this invention is to ²⁰ provide improved means for mounting a computing dial or plate in a scale and relative to the spring supported suspended means.

A further object of this invention is to ²⁵ provide improved means for indicating to the observer the amount of postage required on a package suspended from a scale.

My invention consists in the construction, arrangement and combination of elements ³⁰ hereinafter set forth, pointed out in my claims and illustrated by the accompanying drawing, in which—

Figure 1 is an elevation illustrating the complete device in position for practical use. ³⁵ Figure 2 is a rear view of the spring supported suspending means, dial, and end members of the housing detached from the remaining elements. Figure 3 is a cross-section on the line 3—3 of Figure 1. Figure 4 is a perspective illustrating the rear face of the dial plate and the guard lugs formed thereon. Figure 5 is a face view of the computing dial or plate.

In the construction of the device as shown ⁴⁰ a back plate 15 is employed, which plate is formed with forwardly extending flanges 16 on its longer side margins, said flanges terminating in outwardly rolled hook portions 17. The back plate 15 also is formed with a concavo-convex groove or seat 18 in its central portion, the concaved surface of ⁴⁵ said groove being on the forward surface of said plate. A front plate 19 is provided and is adapted to cooperate with the back plate 15. The front plate 19 is formed on its longer side margins with rearwardly and

inwardly curved rolls 20, which rolls have their free margins spaced slightly from the rear face of said front plate. The front plate and rear plate are adapted to be ⁶⁰ assembled by relative sliding movement longitudinally, the rolls 20 of the front plate engaging snugly and sliding on the hook portions 17 of the flanges of the rear plate, so that the front plate and rear plate are ⁶⁵ held and maintained in parallel spaced relation to form the major portions of the scale housing. Counterpart end members 22, 23 are provided, one of said members being shown in Figure 8. Each of the end members 22, 23 possess a shape and configuration conforming to the outline in plan of the housing composed principally of the assembled back plate 15 and front plate 19; and each of said end members is formed ⁷⁰ with a peripheral flange 24 adapted to engage frictionally an end portion of the housing above described. When the end members are so engaged they complete the housing by closing the end portions thereof. ⁷⁵ Each of the end members 22, 23 is formed with a central hole through which a member to be described later is slidably extended.

A dial plate 26 is provided and is of a width to fit snugly within the housing and of a length considerably less than said housing so that said dial plate is adapted for considerable range of movement longitudinally of and within said housing. The dial plate 26 is formed with a number of spaced ⁸⁰ rearwardly extending lugs 27 on its margins, adapted for sliding contact with the inner surface of the rear plate 15 of the housing, said lugs serving to hold the face of said dial plate in snug contact with the rear face of the front plate 19 and dial plate also is formed at its lower margin with a rearwardly extending ear 28 centrally located and formed with an aperture 29 therein. ⁸⁵ A threaded stem 30 is slidably mounted through the aperture 25 of the top plate 22 and a nut 31 is adjustably mounted on said stem in contact with the upper face of said top plate. The stem 30 is formed with a head 32 at its lower end adapted to be engaged by a retractile coil spring 33 mounted within the housing. The spring 33 is formed with a hook 34 at its lower end and said hook passes through the aperture 29 of the ear formed on the lower end of the dial plate 26. By this means the dial plate is adjustably and yieldingly supported from ⁹⁰ ⁹⁵ ¹⁰⁰ ¹⁰⁵ ¹¹⁰

- the top of the housing. The ear 28 is formed near its inner end with a down-turned stop lug 35 adapted to be engaged by the hook 34 to limit and prevent torsional movement of the spring 33. A rod 36 is extended slidably through the hole 25 of the bottom plate 23 of the housing and said rod is formed at its upper end with a hook 37 engaging the housing 34 of the spring. At 10 its lower end the rod 36 is formed with an eye 38 in which is pivotally secured a hook 39 adapted to be employed in supporting a package or other article to be weighed. A bail 40 preferably is formed from a single 15 length of wire suitably bent and formed between its ends and at its ends having in-turned members 41 adapted to engage pivotally in holes formed in the upper portions of the flanges 16 of the housing.
- 20 On the forward face of the dial plate 26 is a vertically arranged suitable scale 42 which is graduated to suitable denominations of weight and which may be provided with suitable indicia indicating weight. The front plate 19 of the housing is formed with an opening 43 with which the scale 42 of the dial plate registers and through which portions of said scale may be observed and read. The outline of the opening 43 preferably is so formed as to produce an indicator 44 directed toward the scale 42. The dial plate 26 also has on its front face a series of vertical rows of numerals 45, in this instance four in number. The rows of numbers 45 progress in selected sequence from the lower to the upper end of the dial plate and are arranged in transverse rows having certain definite relations to the units of the scale 42. The rows 45 of numerals 40 are arranged in alinement with openings 46 formed in the front plate 19 in transverse alinement with the opening 44 and said numbers are adapted to be read through said opening to determine the amount of postage required in different zones for the package being weighed, the weight of which is indicated through the opening 44. The front plate 19 bears suitable indicia such as 47 indicating the various zones or other units of 45 distance to which the various columns 45 of numerals relate, it being understood that said numerals represent the amount of postage in cents or other denomination.
- 55 A supporting plate 48 is provided and is formed with suitably located holes 49 to receive screws or other securing members by means of which the support may be secured to a wall or other object. The supporting plate 48 is formed with a pair of spaced forwardly extending apertured ears 50, 51, the apertures of which are in vertical alinement. A bracket arm 52 is provided and is formed at one end with a pintle 53 having its ends projecting beyond said bracket arm and pivoted in the apertures of the ears 50, 51. At 60 its other end the bracket arm 52 is formed with a hole 54 adapted to be engaged by the bail 40 of the scale housing, whereby the scale is supported. The lowermost ear 51 of the supporting plate preferably is formed with a plurality of seats 55, radiating from its aperture and adapted to be engaged selectively by the lower margin of the bracket-arm 52, whereby said bracket-arm may be held in any of several selected positions of 75 angularity relative to the vertical plane of the supporting plate 48.
- 70 The tension of the spring 33 and the vertical position of the dial plate 26 and of the scale 42 and figures 45 thereon relative to the openings 44, 46 of the housing may be adjusted by adjustment of the nut 31 on the threaded stem 30.
- 75 Various members of the housing, the dial plate 26, the supporting plate 48 and the bracket 52 may be formed of metal by stamping and pressing, so that a very inexpensive article may be produced, which article will be thoroughly efficient for the purpose for which it is designed. The method of assembling the members of the housing also makes for economy of manufacture. The members of the housing may be suitably finished by enameling or the like and the major portion of the front plate 19 95 may be employed for advertising or other suitable printed matter.
- 90 The groove 18 of the back plate provides space for the spring 33 and for the ear 28 of the dial plate in their vertical movement 100 in the housing.
- 95 I claim as my invention—
1. A parcel post computing scale, comprising a housing formed with transversely alined openings, a spring suspended within said housing, a suspending member secured to the lower end of said spring and projecting outside of said housing, and a dial plate secured to the lower end of said spring and movable vertically in said housing as said spring expands and contracts, said dial plate being formed with a scale indicating weight and readable through one of said openings and also being formed with tabulations indicating amount of postage and readable through others of said openings, said dial plate also being formed with spacing lugs on its rear face slidably engaging the rear wall of said housing.
- 105 110 115 120
2. A parcel post computing scale, comprising a housing formed with transversely alined openings in its front wall, a spring suspended within said housing, a suspending member secured to the lower end of said spring and projecting through the lower end of said housing, and a dial plate secured to the lower end of said spring and vertically movable in said housing as said spring expands and contracts, said dial plate having on its front face a scale indi-
- 125 130

- cating weight and readable through one of the openings of said housing, said dial plate also being formed with tabulations indicating amounts of postage and readable through others of said openings, said dial plate also being formed with spacing lugs extending rearwardly into contact with the rear wall of said housing and holding said dial plate against the front wall thereof.
- 10 3. A parcel post computing scale, comprising a housing formed with transversely alined opening in its front wall, a coil spring suspended within said housing, a supporting member secured to the lower end of said spring and projecting through the lower end of said housing, said spring being formed with a hook at its lower end, a dial plate having a rearwardly extending apertured ear at its lower end, the hook of said spring extending through the aperture of said ear whereby said plate is secured to the spring, said dial plate being formed with a scale and with tabulations readable through the openings of said housing.
- 25 4. A parcel post computing scale, comprising a housing having spaced back and front plates, said front plate being formed with transversely alined openings, a coil spring suspended within said housing, a supporting member secured to the lower end of said spring and projecting through the lower end of the housing, a dial plate having a rearwardly extending apertured ear at its lower end, said spring being formed with a hook at its lower end extended through the aperture of said ear, said dial plate being formed on its front face with a
- scale and tabulations readable through the openings of said housing plate, said back plate being formed with a vertically extending groove to receive said spring and the ear of said dial plate.
5. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement.
- 15 6. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement.
- 20 7. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement, said end plates being formed with peripheral flanges adapted to engage end portions of the front and back plates and the members formed thereon.
- 25 8. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement, said end plates being formed with peripheral flanges adapted to engage end portions of the front and back plates and the members formed thereon.
- 30 9. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement, said end plates being formed with peripheral flanges adapted to engage end portions of the front and back plates and the members formed thereon.
- 35 10. In a scale, a housing comprising back and front plates and end plates, the back plate being formed with forwardly extending flanges on its side margins, outer margins of said flanges being turned outwardly, the front plate having its side margins rolled rearwardly and inwardly and adapted to engage the outwardly turned portions of the flanges of the back plate, whereby said back plate and front plate may be assembled and connected by endwise sliding movement, said end plates being formed with peripheral flanges adapted to engage end portions of the front and back plates and the members formed thereon.

Signed at Des Moines in the county of Polk and State of Iowa, this 9th day of April, 1920.

CHARLES H. COLSON.
